UNITED STATES PATENT OFFICE.

WILLIAM A. STEFFA, OF ROCKVALE, ILLINOIS.

COMBINED FEED-COOKER AND SCALDER.

SPECIFICATION forming part of Letters Patent No. 366,042, dated July 5, 1887.

Application filed May 5, 1886. Serial No. 201,182. (No model.)

To all whom it may concern:

Be it known that I, WILLIAM ARTHUR STEFFA, of Rockvale, Oregon P. O., in the county of Ogle and State of Illinois, have invented a new and useful Improvement in a Combined Feed-Cooker and Scalder; of which the following is a full, clear, and exact description.

Reference is to be had to the accompanying drawings, forming a part of this specification, in which similar letters of reference indicate corresponding parts in all the figures.

Figure 1 is a plan view of my improvement arranged as a hog-scalder. Fig. 2 is a sectional side elevation of the same taken through the broken line $xx'xx'$, Fig. 1. Fig. 3 is a sectional rear elevation of the same. Fig. 4 is a front elevation of the same arranged as a feed-cooker, parts being broken away.

20 The object of this invention is to provide a combined feed-cooker and hog-scalder constructed in such a manner that it can be readily used for either purpose, and which shall be simple in construction and convenient in use.

25 The invention consists in the construction and combination of various parts of the feed-cooker and hog-scalder, as will be hereinafter fully described.

The furnace A is made with an upward offset in its bottom, and is formed by securing end and bottom plates to and between side plates. The end and bottom plates are made with flanges upon the outer sides of their side edges, which are perforated for the passage 35 of the long bolts B. The long bolts B also pass through holes along the bottom and end edges of the side plates. By this construction the fastening bolts B will all be outside the furnace, and thus not liable to be burned off or 40 otherwise injured by the fire. The upward offset of the furnace bottom serves as a bridge-wall to project the products of combustion against and around the water-tank hereinafter described. The fire-grate is formed of a perforated plate, C, having ribs D, only one being shown, formed upon its lower side, so that the said grate can be used or removed as the character of the fuel may require.

E is the furnace-door, which is hinged to the 50 forward edge of one side plate of the furnace

and closes against the forward edge of the other side plate. In the furnace-door E are formed two sets of draft-openings, F, one above and the other below the level of the grate C, and which are closed by sliding dampers G, 55 so that the draft can be introduced above or below the said grate, as the kind of fuel being used may require. The furnace A is supported upon legs H, or frames of such a length as to raise the bottom of the said furnace to a sufficient height above the floor or ground. The rear end of the furnace is provided with a narrow top plate, I, through which is formed a narrow opening, J, extending nearly across the furnace, and provided with a collar to receive a wide flattened pipe, K, so that the products of combustion will pass back evenly along the bottom and sides of the tank L instead of being concentrated toward a small discharge-opening, and will thus heat all parts 70 of the said tank equally. The tank L is made with flaring sides and ends and with a flange, M, upon the middle or upper part of its outer surface to rest upon the upper edge of the furnace, and thus suspend the said tank within 75 the said furnace. With this construction spaces will be left between the sides and ends of the tank and the sides and ends of the furnace, so that the products of combustion can pass all around the said tank and thus 80 heat it very quickly, and with a comparatively small amount of fuel. The tank L is made in one piece, and has a discharge-opening in the lower part of one side, in which is secured the inner end of a short discharge-tube, N, through which the liquid or semi-fluid contents of the said tank can be drawn off. When the feed is to be steamed, a perforated false bottom, O, is placed in the lower 85 part of the tank L and supported at the desired height by short legs P, attached to it and resting upon the bottom of the said tank, as shown in Fig. 4, so as to support the feed above the water placed in the lower part of the said tank. The tank L is provided with 90 a cover, Q, which is hinged at the ends of one side edge to lugs formed upon or attached to the said tank L, so that the said cover can be turned back into a horizontal position, as shown in Figs. 1 and 3, to serve as a table. 100

The cover Q is strengthened by cross-bars R, secured to its upper side near its ends. To the cross-bars R, near their ends, are attached staples S, to receive bars T, which are kept 5 from sliding out of the said staples S when the cover Q is raised by cross-pins U, attached to them in such positions that when the cover Q is turned back a little past a vertical position the lower ends of the said bars T will 10 rest against the side of the tank or furnace, and thus prevent the said cover from being turned back too far. When the cover Q is turned back into a horizontal position, the bars T are withdrawn from the staples S, their 15 lower ends are placed in recesses V in the legs H, and their upper ends are placed in recesses W in the cross-bars R, as shown in full lines in Fig. 3 and in dotted lines in Fig. 2, so as to support the said cover firmly in 20 place. With this construction the cover Q is adapted to serve as a table to support a hog while the hair is being removed.

To the upper side of the forward end of the cover Q are attached staples X, to receive 25 hooks Y, attached to the upper ends of the side bars of the frame Z when the said cover is adjusted as a table. The frame Z is made of such a length as to reach nearly to the ground when hung from the staples X. To 30 the lower end of the frame Z is hinged, by a round, a, or other suitable means, the end of a frame, b. To the round a is also hinged short legs or braces c, the free ends of which are pointed and rest upon the ground to hold the 35 lower end of the frame Z from being forced inward when in use. To the frame b is attached a shelf or chair, d, of sufficient size to receive a hog, and in such a position as to be a little above the table Q when the frame b is 40 raised against the end of the said table, so that the hog can slide or be readily drawn from the said chair to the said table. In recesses in the upper edges of the ends of the tank L, and close to the hinged edges of the 45 cover Q, is journaled a shaft, e, to which are attached, or upon it are formed, arms f, which are bent at an angle, as shown in Fig. 3, so as to rest against the side and bottom of the tank L when turned down into the said tank. 50 The shaft e and arms f serve as a cradle for lowering the hog into and raising it from the tank L. To one end of the shaft e is attached a crank-arm or lever, g, by means of which the cradle e f can be readily turned into and out 55 of the tank L.

In using the machine for scalings hogs, the cradle e f is adjusted in place in the tank L, and when the water in the said tank is sufficiently heated the cover Q is turned back 60 and secured in a horizontal position, and the frames Z b are connected with the said cover. The hog is then laid upon the chair d, and the outer end of the frame b is raised, depositing the hog on the table Q. The hog is 65 then lowered into the tank by means of the cradle e f, or by other suitable means, and

when sufficiently scalded it is raised from the tank L by means of the cradle e f and placed upon the table Q, where the hair is removed in the ordinary manner.

Having thus fully described my invention, what I claim as new, and desire to secure by Letters Patent, is—

1. A scalding and feed-cooking device comprising the furnace A, having an open top and a wide smoke-discharge aperture, J, at its rear end, the tank L, having a flange, M, around its outer side, supporting it upon the top edge of the furnace, the sides and ends of the tank being inclined, as shown, to 75 permit the free passage of the heat entirely around it in passing to the aperture J, the horizontal removable shaft e, having reduced portions resting in recesses in the ends of the tank near one side thereof, and provided 80 with the angular arms f, resting close to the side and bottom of the tank, and the cover Q, forming the table hinged to the side of the tank next to the shaft e, substantially as set forth.

2. The combination, with the tank and its support, of the hinged cover Q, having staples S, and the removable transverse bars T, loosely mounted therein and having stop-pins, whereby when the bars are held by the staples the 95 cover may be raised and supported, and by lowering the cover to a horizontal position and removing the bars and placing them, as described, below the cover, a table may be formed, substantially as set forth.

3. The combination, with the hot-water tank, and the table to one side thereof, of a vertically-swinging frame pivoted at its lower end below the table, and having a shelf or chair, the front edge of which is approximately in line with the table when the frame is raised to a perpendicular position, substantially as set forth.

4. The combination, with the hot-water tank, and the cover hinged thereto, of a detachable vertically-swinging frame removably secured to the cover, and having a shelf or chair adapted to deliver the article held thereby upon the cover when the frame is raised to a vertical position, substantially as set forth.

5. The combination, with the hot-water tank, and the table at one side thereof, of a frame pivotally connected with said table, and provided with pointed braces to engage 120 the floor or ground to prevent slipping, and with a shelf or chair, d, to deliver the hog upon the table when the frame is raised to a vertical position, substantially as set forth.

6. The combination, with the angular scalding or feed-cooking tank having notches or recesses in the upper edges of its ends, and the cover forming a table hinged to the upper edge of the tank at the side nearest the notches, of a removable shaft, e, extending 125 along the inner side of the tank below its upper edge and having its bearings in said

notches, and the angular arms *f* on the shaft resting close to the side and bottom of the tank, substantially as set forth.

7. In a combined feed-cooker and scalding tank, the combination, with the hinged cover *Q*, having staples *X*, and the supporting-bars *T*, of the frame *Z*, having hooks *Y*, engaging with the said staples, the pointed braces *e*, hinged to the said frame, and the frame *b*,

hinged to the frame *Z*, and provided with a chair, *d*, substantially as herein shown and described, whereby a hog can be readily raised and deposited upon the said cover, as set forth.
